UNITED STATES PATENT OFFICE.

HOWARD M. BARBER, OF WESTERLY, RHODE ISLAND, ASSIGNOR TO C. B. COTTRELL & SONS COMPANY, OF WESTERLY, RHODE ISLAND, A CORPORATION OF DELAWARE.

PLATE-CLAMPING MECHANISM FOR PRINTING PRESSES.

Application filed December 31, 1925. Serial No. 73,578.

The object of my invention is to provide plate cylinders with novel plate clamping means whereby one or a group of plates may be locked to the cylinder in one operation, thereby materially facilitating the laying and removal of the plates when the cylinder carries a full complement.

My invention includes means whereby the intermediate side plate clamps may be adjusted with respect to the inner and outer plate clamps, said intermediate plate clamps also having a limited free longitudinal movement so that when a full complement of plates is to be locked to the cylinder, it may be accomplished in one operation through the medium of said plates, by moving the outer side plate clamps inwardly along the cylinder.

A practical embodiment of my invention is represented in the accompanying drawings, in which:

Fig. 1 represents a detail side view of a plate cylinder with my improved plate clamping means applied thereto, a full complement of three plates being shown locked to the cylinder by utilizing the inner, outer and intermediate side plate clamps.

Fig. 2 represents a detail longitudinal section taken in the plane of the line II—II of Fig. 4, looking in the direction of the arrows.

Fig. 3 represents a detail transverse section taken in the plane of the line III—III of Fig. 2, looking in the direction of the arrows.

Fig. 4 represents a detail end view of the cylinder partly in section.

Fig. 5 represents a detail transverse section taken in the plane of the line V—V of Fig. 1, looking in the direction of the arrows.

Fig. 6 represents a detail transverse section taken in the plane of the line VI—VI of Fig. 1, looking in the direction of the arrows.

The shell of the plate cylinder is denoted by 1, the middle or inner circumferential series of fixed side plate clamps by 2, the outer circumferential series of longitudinally adjustable side plate clamps by 3, and the two intermediate circumferential series of longitudinally adjustable side plate clamps by 4 and 5.

Each of the outer side plate clamps 3 is engaged with a screw shaft 6, rotatably

mounted in the cylinder bearer 7. The inner threaded portion of this screw shaft 6 projects into an undercut groove 8, the side walls of which form guides for the plate clamp 3. The two screw shafts 6 of each pair of side clamps 3 around the cylinder are connected to move in unison by providing the shafts with pinions 10, meshing with a common gear 11, rotatably mounted on a stud axle 9. A spring pressed pawl 12 engages the gear 11 to hold the two screw shafts 6, of a pair, in their adjusted position. Each screw shaft 6 is shaped at its outer end for the reception of a suitable wrench or other tool, not shown herein, for turning the said shafts to move the outer side clamps inwardly or outwardly along the cylinder, as desired. A spring pressed pawl 12 engages the gear 11 to yieldingly hold the same in the desired rotative adjustment.

Each of the intermediate side plate clamps 4 engages a screw shaft 13 rotatably mounted and having a limited free endwise movement in suitable bearings 14 and 15 at the inner and outer ends of the undercut groove 16, the side walls of which form guides for the movement of the side plate clamp 4 along the cylinder. Each screw shaft 13 is provided with an element, in the present instance a pinion 17, exposed through a circumferential groove 18 in the cylinder for manual engagement by a suitable tool, such as a rack, to rotate the pinion and thereby the shaft, to adjust the clamp inwardly and outwardly along the cylinder and to adjust the same for plates of different widths.

Coacting devices on the shaft and cylinder are provided for yieldingly holding the screw shaft against unintentional rotation, which devices are herein shown as a wide faced toothed wheel 19, fast on the shaft and a spring pressed yielding pin 20 engaged therewith. The toothed wheel 19 is sufficiently wide to remain at all times in engagement with the pin 20 between the limits of the free endwise movement of the screw shaft 13.

Each of the other series of intermediate side plate clamps 5 is mounted similarly to each of the intermediate side plate clamps 4, the screw shaft in this instance being denoted by 21, the end bearings by 22, 23, the undercut groove by 24, the shaft rotating element by 25 and the coacting devices by 26, 27.

From the above description it will be seen that the clamps 3, 4 and 5 may be adjusted along the cylinder to any size plate within predetermined limits.

The procedure for locking a longitudinal row of three plates 28, 29, 30 to the cylinder in one operation is as follows:—

The clamps 3, 4 and 5 are adjusted on their screw shafts so that they will clear the plates when the screw shafts 13 and 21 are moved endwise to their outer limits.

The plates are then laid in position on the cylinder, the plate 28 between the inner fixed clamps 2 and the intermediate clamps 4, the plate 29 between the intermediate clamps 4 and the intermediate clamps 5 and the plate 30 between the intermediate clamps 5 and the outer clamps 3. The clamps 3 are then moved inwardly by rotating the shaft or shafts 9 and thereby the screw shafts 6 until the plates are securely locked, this being accomplished by the limited free longitudinal movement of the intermediate clamps 4 and 5.

It will be understood that a single plate can be locked in any one of the three positions or that two of the plates can be locked in any of the three positions by the manipulation of the several clamps.

It will be seen from the above description that where the cylinder carries a full complement of plates the laying and removal of the plates is materially facilitated, as the plates may be locked to or unlocked from the cylinder in one operation.

It is evident that various changes may be resorted to in the construction, form and arrangement of the several parts without departing from the spirit and scope of my invention; hence, I do not wish to be limited to the particular embodiment herein shown and described, but

What I claim is:—

1. A cylinder and plate clamping means therefor, including a double side plate clamp arranged to engage two adjacent plates, said cylinder having a longitudinal groove forming a guide for the clamp, and a circumferential groove, end bearings in said longitudinal groove, a single threaded screw shaft having a limited free endwise movement in said end bearings and engaging the clamp for imparting endwise movement thereto, and means on said shaft exposed through

said circumferential groove for use in the manual rotation of said shaft.

2. A cylinder and plate clamping means therefor, including a double side plate clamp arranged to engage two adjacent plates, said cylinder having a longitudinal groove forming a guide for the clamp, and a circumferential groove, end bearings in said longitudinal groove, a single threaded screw shaft having a limited free endwise movement in said end bearings and engaging the clamp for imparting endwise movement thereto, means on said shaft exposed through said circumferential groove for use in the manual rotation of said shaft, and means for yieldingly holding the shaft against unintentional rotation between the limits of its free endwise movement.

3. A cylinder and plate clamping means therefor, including a double side plate clamp arranged to engage two adjacent plates, said cylinder having a longitudinal groove forming a guide for the clamp, and a circumferential groove, end bearings in said longitudinal groove, a single threaded screw shaft having a limited free endwise movement in said end bearings and engaging the clamp for imparting endwise movement thereto, and a pinion on said shaft exposed through said circumferential groove for use in the manual rotation of the shaft.

4. A cylinder and plate clamping means therefor, including a double side plate clamp arranged to engage two adjacent plates, said cylinder having a longitudinal groove forming a guide for the clamp, and a circumferential groove, end bearings in said longitudinal groove, a single threaded screw shaft having a limited free endwise movement in said end bearings and engaging the clamp for imparting endwise movement thereto, a pinion on said shaft exposed through said circumferential groove for use in the manual rotation of the shaft, a wide faced toothed wheel fixed on said shaft, and a spring pressed yielding pin engaged therewith to yieldingly hold the screw shaft against unintentional rotation between the limits of its free endwise movement.

In testimony, that I claim the foregoing as my invention, I have signed my name this 29th day of December, 1925.

HOWARD M. BARBER.
